Inventor
George P. Towle

UNITED STATES PATENT OFFICE.

GEORGE P. TOWLE, OF BOSTON, MASSACHUSETTS, ASSIGNOR TO HIMSELF
AND RUFUS H. SPALDING, OF SAME PLACE.

IMPROVEMENT IN CLOTHES-WRINGERS.

Specification forming part of Letters Patent No. 35,911, dated July 15, 1862.

To all whom it may concern:

Be it known that I, GEORGE P. TOWLE, of the city of Boston, in the county of Suffolk and State of Massachusetts, have invented an Improvement in Clothes-Wringers; and I do hereby declare that the following, taken in connection with the drawing, which accompanies and forms part of this specification, is a description of my invention sufficient to enable those skilled in the art to practice it.

My invention consists in the arrangement and combination of parts herein described, by which the upper roll of a clothes wringer or presser is forced down upon the lower roll more conveniently and cheaply than has been hitherto practiced, and by which the upper roll is made self-adjustable to permit a greater opening between the rolls at one end than at the other.

The drawing is a front view of a wringer embodying my invention, a portion of one of the sides or posts, *a*, being removed to show parts inclosed therein. The posts of the wringer are united or are framed together by the cross-girts *b*, and the rolls *c* and *d* are so arranged as to be capable of rotation in bearings in the post. The lower roll, *d*, can have only a rotary movement in its bearings; but the bearings for the upper roll, *c*, being slotted, permit vertical as well as rotary movement to *c*. Holes are bored in the posts from the upper ends thereof into the slotted bearings of roll *c*, so that pins *e*, inserted in said holes, rest or bear against or upon the shaft of roll *c*, within its bearings, and project beyond the tops of posts *a*. A wooden spring, *f*, is so arranged over pins *e* as to rest thereupon, and the flat link *h*, which is hinged to the upper girt, *b*, and to the cam-lever *g*, passes through the spring *f* and keeps it from being materially displaced. The cam-lever is of such form that

its movement to depress the spring *f* constantly increases from the position in which it is shown in the drawing till its lever is made to assume a horizontal position in the opposite direction. The introduction of clothes, it will be seen, tends to separate the rolls by bending the spring *f* under the cam-lever *g*, and by turning the cam-lever *g*, it will be seen that the spring *f* is made to resist more powerfully the separation of the rolls. It will also be seen that when more thickness of clothes is introduced between the rolls at one end than at the other, a self-adaptation of the rolls to suit the circumstances is found by the greater deflection of the spring *f* at one end than at the other.

The cam-lever *g* can be set in any desired position, and should be so set as to bring a greater stress upon the spring when passing thin pieces through the machine than when passing thick ones through. The rolls shown are formed by surrounding the shafts with wooden cylinders, which are kept, by pins, from turning on the iron shafts, and the cylinders are covered with a layer of felting cemented thereunto.

The wringer is secured to the tub by bent clamps, which pass through the posts *a* and are operated by means of thumb-nuts to clamp the wringer to the tub.

Having described my invention, I claim as new—

The arrangement and combination, in a clothes wringer or presser, as shown and described, of the yielding-surfaced roll *c*, the bearing pins *e*, the wooden spring *f*, the link *h*, and the cam-lever *g*, all operating together as set forth.

GEO. P. TOWLE.
